mesne assignments, to Erhardt L. Becker,
Flushing, Charles F. Kolb, Great Neck, Robert
B. Eddy, Flushing, and Kurt Beyrodt, Williston
Park, N. Y.

Application December 1, 1948, Serial No. 62,842

4 Claims. (Cl. 4—180)

1

This invention relates to therapeutic bath apparatus and particularly to improvements thereto in whereby the application of water currents with entrained air to the body of a patient undergoing treatment is more effectively accomplished.

In U. S. Letters Patent No. 2,237,435 and No. 2,237,436 to Floyd W. Ille and No. 2,428,004 to Kurt Beyrodt, apparatus for, the procedure employed, and the benefits resulting from the application of jets of water containing entrained air to the human body and parts thereof are fully described. Apparatus of this type has developed wide application and is generally employed in hospitals and by physicians throughout the country. The benefits of hydromassage to patients suffering from various conditions is widely recognized.

It is the object of the present invention to provide an improvement in such apparatus whereby the jet of water and entrained air is oscillated to facilitate the application of the jet and to develop and enhance the massaging effect thereof as applied to the surfaces treated.

Other objects and advantages of the invention will be apparent as it is better understood by reference to the following specification and the accompanying drawing, in which

Fig. 1 is an elevation, partially in section, illustrating the apparatus;

Fig. 2 is a section on the line 2—2 of Fig. 1;

Fig. 3 is a section on the line 3—3 of Fig. 2;

Fig. 4 is a plan view of the apparatus with a portion of the mechanism removed, to facilitate illustration; and

Fig. 5 is a similar view showing another position of the parts.

The particular means for producing the water jet or jets with entrained air and the form of the tank employed constitute no part of the present invention. The jet-producing mechanism as disclosed in the Ille Patents Nos. 2,237,435 and 2,237,436 may be employed, or any other suitable mechanism may be substituted therefor. Similarly the tank, with slight modifications to conform to the invention, may be the convoluted tank of the Ille patents or any desired modification thereof.

In carrying out the invention, therefore, I provide a tank 5 of suitable shape and configuration with a rim 6, preferably formed as indicated to support the jet-producing mechanism or turbine ejector indicated generally at 7. A guide rail 8 is supported by brackets 9 in spaced relation to and surrounding the lower edge of the tank. The turbine ejector 7 comprises a motor housing 10 connected by a tube 11 to the turbine housing 12. An air pipe 13 also extends from the housing 10 to a point near the outlet from the housing 12 where it is supported by a bracket 14.

2

When in operation, water is drawn into the housing 12 and ejected at high velocity past the end of the air pipe 13, forming a jet with occluded air bubbles which may be directed upon any portion of the patient's anatomy which is to be treated. Further description of the turbine ejector is unnecessary since it is fully described in the Ille Patents Nos. 2,237,435 and 2,237,436. Any suitable variation of this device may be utilized.

To support the mechanism as described, so that it may be moved about the rim of the tank, located in any desired position, and adjusted vertically, I prefer to utilize the mechanism as shown in the Beyrodt Patent No. 2,428,004, although other suitable means may be employed. As illustrated in the drawing, the motor housing 10 is connected to an arm 15 which is supported on a tubular member 16 held in adjusted vertical position by a clamp 17 which is locked by a screw 18 and hand wheel 19. The weight of the mechanism is preferably counterbalanced by a spring within the tubular member 16, as in the Beyrodt Patent No. 2,428,004. This spring is not shown in the drawing because it forms no part of the present invention.

The tubular member 16 extends through a housing 20. Within the housing, a carriage 21 is secured to a boss 22 and carries rollers 23 which are adapted to engage the rim 6 of the tank. Thus, the housing and the mechanism supported thereon may be shifted readily about the rim of the tank to any desired position.

To lock the housing of the mechanism in any particular position, a shoe 24, having a spring 25 on its upper face, is pivoted at 26 and carries an arm 27 with a roller 28 thereon. A cam 29 is mounted on a shaft 30 which also carries a handle 31 to effect operation of the shoe. The housing 20 is preferably recessed at 32 to receive the handle when in the position indicated in Fig. 1, that is, with the mechanism locked to the rim 6 of the tank 5.

A rod 33 is pivoted at 34 on the cam 29 and extends into a tube 35, where it engages a spring 36 secured at its lower end within the tube. The lower end of the tube is pivoted at 37 to a bell crank 38 pivotally mounted at 39 on a bracket 40. An arm 41 of the bell crank is adapted to engage the rail 8. Because of the resiliency of the springs 25 and 36 when the arm 31 is in the position indicated in Fig. 1, the shoe 24 and the arm 41 of the bell crank 38 engage the rim 6 and the rail 8 and firmly lock the mechanism in the adjusted position on the tank 5. The mechanism as described is that shown in the Beyrodt Patent No. 2,428,004, and no claim is made thereto in the present application.

The present invention is directed to mechanism for oscillating the jet produced by the mechanism

indicated generally at 7. Upon the arm 15 a motor 42 is mounted. It includes a speed reducing mechanism, the details of which form no part of the present invention, such mechanism being commonly employed in connection with motors to effect desired reduction in the speed of the operating shaft. A crank 44 is supported on the low speed shaft 45 and rotates when the motor 42 is in operation. A crank pin 46 is connected by a link 47 to a pin 48 which is offset from the axis of the reaction crank 49. The latter is mounted on a stud 50 extending upwardly from the sleeve 51, which is mounted in pin bearings 52 in the arm 15. The arm rests upon a thrust bearing consisting of ball races 53 and balls 54, the lower race 53 engaging a flange 55 of the sleeve 51. The flange 55 rests upon a friction disk 56 of rubber or other suitable material which in turn engages a flange 57 secured to the tube 16. Thus, the sleeve 51 is normally fixed with reference to the tubular member 16, but by means of a handle 58 secured to the flange 55 the sleeve 51 may be shifted about the axis of the tube 16 to vary the position of the pin 48 with reference to the crank 44. When the motor 42 is in operation, the crank 44 rotates and, since the position of the pin 48 is fixed, the arm 15 and the jet producing mechanism indicated generally as 7 oscillates about the axis of the tube 16. This in turn results in an oscillating jet which, when directed upon the anatomy of the patient, produces a massaging effect and resultant improvement in the action of the jet in effecting the desired treatment. In order to shift the arc of oscillation relatively to the tank 5, it is necessary merely to actuate the handle 58 and thereby shift the position of the pin 48. This may be accomplished while the motor 42 is idle or while it is in operation, to modify the direction and the arc of travel of the jet in relation to the anatomy of the patient.

This arrangement also acts as a safety device to prevent injury to any person interfering with the oscillating motion of the turbine ejector. If the turbine ejector 7 cannot oscillate due to mechanical interference, the motion of the crank 44 and crank pin 46 will be transmitted through link 47 to pin 48 and impart an oscillating motion to the reaction crank 49, sleeve 51, flange 55 and handle 58. The interference momentum to be exerted on turbine ejector 7 is no greater than the momentum set up by the friction between flange 55 and friction disc 56. It is also evident that motor burn-outs can be prevented in case of interference by keeping the power dissipated by friction disc 56 within the normal power output of the motor.

The apparatus as described is simple and effective and results in a considerable improvement in the effectiveness of the treatment and the ease with which the operator may manipulate the jet to accomplish the desired purpose.

Various changes may be made in the details of the structure as described and in the mode of operation thereof without departing from the invention or sacrificing the advantages thereof.

I claim:

1. In a therapeutic bath apparatus consisting of a tank, motor-driven jet-producing mechanism, a supporting arm connected to the jet-producing mechanism and a support therefor mounted on the tank, the improvement consisting of a sleeve surrounding the support, friction means

between the sleeve and the support to normally hold them in fixed relation, manual means for moving the sleeve about the axis of the support, an antifriction bearing between the sleeve and arm, a reaction crank carried by the sleeve, a second motor mounted on the arm and means actuated by the second motor and connected to the reaction crank whereby the jet-producing means is oscillated and the arc of oscillation is shifted relatively to the tank by adjustment of the manual means.

2. In a therapeutic bath apparatus consisting of a tank, motor-driven jet-producing mechanism, a supporting arm connected to the jet-producing mechanism and a support therefor mounted on the tank, the improvement consisting of a sleeve surrounding the support, friction means between the sleeve and the support to normally hold them in fixed relation, manual means for moving the sleeve about the axis of the support, an antifriction bearing between the sleeve and arm, a reaction crank carried by the sleeve, a second motor mounted on the arm and means actuated by the second motor consisting of a crank and a link connected to the reaction crank whereby the jet-producing means is oscillated and the arc of oscillation is shifted relatively to the tank by adjustment of the manual means.

3. In a therapeutic bath apparatus, a motor-driven jet producing mechanism, a supporting arm rigidly connected to the jet-producing mechanism, a vertically adjustable support affording a pivotal axis for the supporting arm, a sleeve surrounding the adjustable support, an antifriction bearing between the sleeve and arm, a second motor mounted on the supporting arm, a crank connected thereto, a pin on the sleeve offset from the pivotal axis, and a link connecting the crank and pin.

4. A therapeutic bath apparatus consisting of a tank, a motor-driven jet-producing mechanism, a supporting arm rigidly attached to the jet-producing mechanism, a vertically adjustable support for the arm mounted in adjustable relation on the tank, a sleeve surrounding the support, an antifriction bearing between the sleeve and arm, friction means between the sleeve and support to normally hold them in fixed relation, manual means for moving the sleeve about the axis of the support, a reaction crank carried by the sleeve, a second motor mounted on the arm, and means actuated by the second motor and connected to the reaction crank whereby the jet-producing means is oscillated and the arc of oscillation is shifted relatively to the tank by adjustment of the manual means.
